APPARATUS FOR REMOVING SNOW
AND THE LIKE

Edward R. Greer, Wayzata, Minn.

Application July 20, 1945, Serial No. 606,061

7 Claims. (Cl. 37—43)

1

This invention relates to new and useful improvements in apparatus for removing snow and other materials from roadways and other areas and involves the use of hot combustion gases under pressure to facilitate lateral or vertical movement and disposal of the material being handled. This apparatus is of the general type disclosed in this applicant's United States Letters Patent No. 2,404,287.

Among the new features are the provision of a self-contained jet unit adapted for attachment to a moldboard or to a rotary snow plow, and the provision for use of part or all of the jet blast to actuate a turbine motor which may be employed to drive a snow plow rotor.

An object of the present invention is to provide an apparatus having in combination a moldboard or guided passage and a hot combustion gaseous pressure means for transferring or assisting in the transfer or disposal of the material.

Other objects of the invention are to provide an apparatus incorporating one or more of the above recited features and these and other objects will be more apparent from the specification, drawings and claims. The specific embodiments hereinafter described and shown are merely illustrative of the invention involved and may be widely varied to meet satisfactory and specific design requirements.

Other objects of the invention will appear from the following description and the accompanying drawings and will be pointed out in the annexed claims.

In the accompanying drawings there has been disclosed a structure designed to carry out the various objects of the invention, but it is to be understood that the invention is not confined to the exact features shown, as various changes may be made within the scope of the claims which follow.

In the drawings:

Figure 1 is a perspective view of a rotary snow plow with the hot combustion pressure gas device applied thereto, said device being indicated in dotted lines;

Figure 2 is a detailed sectional view of the combustion device showing its association with the vertical chute and with the blades of the snow plow rotor;

Figure 3 is a view showing the outlet of the combustion gas device impinging upon the turbo-rotor vanes and diagrammatically indicating in dotted lines the reduction gears associated with the turbo-rotor to drive the shaft of the rotor blades;

2

Figure 4 is a horizontal sectional view on the line 4—4 of Figure 3 and showing the gear relationship;

Figure 5 is a modification of the driving mechanism shown in Figure 3, but using epicyclic or planetary gear train to drive the rotor blades; and

Figure 6 is a horizontal sectional view on the lines 6—6 of Figure 5.

This invention is more particularly directed to the employment of a jet of hot combustion gases discharged under pressure adjacent the moldboard or guide means of a snow plow. There are several common types of snow guides, one is the V-type which is placed at the apex at the front of a railway engine, or a highway truck, or tractor. Another is the laterally positioned single moldboard usually borne by a highway truck or tractor. Another form is a chute placed above a snow-receiving opening in which is mounted a bladed rotor to receive the snow and upwardly project it through a stack which discharges the snow at one side.

In Figures 1 and 2 there is disclosed a form of device for handling snow or other material. Therein is shown a sidewalk rotary snow plow which is now in use and forms no part of this invention save that the novel combustion chamber and jet are applied thereto.

This old form of sidewalk rotary snow plow briefly consists of a two-wheel structure with an internal combustion engine mounted thereon. The engine is adapted to drive the two-wheels through a clutch mechanism and also drives the blades 120 which are centrally disposed within a housing 121 with funnel shaped sides substantially surrounding it and which are adapted to direct the snow to the rotor blades as the plow is manually guided into the snow by an operator walking behind the handle bars 122. The snow is forcibly moved by the engine-driven blades 120 upwardly through a chute 123 and is provided with a hood 124 having an open side and top and which is rotatable upon the chute 123 so that the snow can be directed to one side or the other of the sidewalk snow plow. This old form of sidewalk snow plow employs an air compressor to deliver cooling air to the single cylinder air-cooled engine and also has a magneto delivering electricity to the spark plug of the engine. Thus, this old form of sidewalk snow plow not only provides a supply of air under pressure but also supplies electrical energy whereby there is a source of each for use with the novel

combustion chamber which has been adapted thereto.

The novel combustion unit is borne by a base plate 125 fixed to the supporting plate 126 of the old form of sidewalk snow plow. This base plate 125 is preferably mounted behind one of the sides 127 which surround the central opening.

The base plate 125 has integrally formed therewith the wall 128 of the combustion chamber which is substantially pear-shaped in form. The outer housing 129 at its lower end has a flanged portion 130 which is fixed to the base plate 125 and the housing 129 upwardly extends and encloses the combustion chamber wall 128. At the upper ends of the housing 129 and combustion chamber wall 128 there is provided an expansion joint. The jet nozzle 131 is received within the upper open end of the combustion chamber and the connection between this nozzle 131 and combustion chamber wall is preferably one that permits ready removal and replacement of the nozzle. The upper open end of the nozzle 131 is adapted to discharge hot gases in the path of the short blades 120 of the snow plow rotor, thus converting the rotor blades into a semblance of an impact type of turbo-rotor. The combustion gases impacted from the combustion chamber thus in part engage the blades 120 and in part directly pass upwardly into the chute 121 to provide a blast to accelerate snow removal.

A mixture of atomized fuel and air under pressure is received within the combustion chamber through aligned apertures in the chamber wall 128 and the housing 129. The atomizer 132 is mounted upon the inner end of a fuel pipe 134. The supply of air under pressure is delivered by the air pipe 133 to the space around the spray nozzle and enters the combustion chamber with the atomized fuel, and the air under pressure thus also enters the space between the chamber wall 128 and the housing 129. The liquid fuel is supplied to the atomizer by the pipe 134 from the same fuel tank on the sidewalk snow plow while air under pressure is supplied to the pipe 133 by the usual air compressor carried by the sidewalk snow plow. The ignition of the atomized fuel is effected by the spark plug 135 mounted in the base plate 125 and projecting within the combustion chamber. The source of the electrical energy for the spark plug is the electric system of the sidewalk snow plow. As above described, the combustion gases upwardly pass through the Venturi tube or nozzle 131 and not only forcibly assist in the rotation of the vanes 120 but also blow the snow through the chute. The force of the combustion gases may tend to rotate the vanes faster than the normal R. P. M. of the rotor but that is merely analogous to an automobile descending a hill with the gears in mesh and without declutching.

In Figures 3 and 4 there is disclosed a modification of a driving means for the blades 120 of the sidewalk snow plow. Broadly considered it consists of a vaned turbo-rotor driving the blades 120 through reduction gearing. The shaft 136 of the form of sidewalk snow plow has pinned thereto a hub 137 which carries the four blades 120. In this novel modification a turbo-wheel 138 having peripheral blades 139 is idly borne by the shaft 136. The hub 140 of the turbo-wheel is provided with peripheral gear teeth 141 which mesh with the teeth of a larger gear 142 pinned to a stub-shaft 143 mounted in a bearing in a housing 144. Likewise, pinned to the stub-shaft 143 is a pinion 145 meshing with a gear 75

146 having its hub pinned to the main shaft 136. These stub shafts and associated pinions are duplicated upon each side of the main shaft 136. The Venturi nozzle 131 shown on the left in Figure 3 upwardly discharges the combustion gases which impact the vanes 139 of the turbo-wheel 138, thus forcibly rotating it in a clockwise direction as shown in Figure 3. This moment of rotation is imparted to the reduction gearing consisting of the pinion 141, duplicate gears 142 and stub shafts 143 and their pinions 145 and finally to the main gear 146 pinned to the shaft 136 which drives the rotary snow blades 120. This reduction gearing imparts considerable power to the blades 120.

Another modification of drive of the rotary snow plow blades 120 is shown in Figures 5 and 6 wherein there is disclosed a planetary form of reduction gearing.

The planetary gearing includes a vaned turbo-rotor 150 whose curved vanes 151 are in the path of the combustion jet from the Venturi tube 152. The hub 153 of the turbo-rotor is borne by bearings 154 mounted upon the hub 155 of a rotatable spider 156 which carries three stub shafts 157 upon each of which is rotatably mounted a similar gear 158. The peripheral teeth of each gear 158 mesh both with a pinion 159 and with the internal teeth 160 of the outer fixed gear. This outer gear is shown as bolted to the frame members 161 of the sidewalk plow while the inner pinion 159 is fixed to the hub 153 of the turbo-rotor 150.

This gearing of the epicyclic type gives power to the vanes 120 in their removal of snow.

Since the jet engages a turbo-rotor of the impulse type the jet gases exhausting from the turbo-rotor blade are still traveling in the direction of snow discharge at a much higher velocity than the snow leaving the rotary plow blades. The energy in this exhaust then materially assists in accelerating and dissipating the snow.

The impulse type of turbines shown apply heat to the turbine vanes for only a small fraction of each rotation period giving plenty of time for the blades to cool, as well as effecting a turbine exhaust containing useful energy available for use in assisting snow discharge.

It will be apparent to those skilled in the art that I have accomplished at least the principal objects of my invention, and it will also be apparent to those skilled in the art that the embodiments herein described may be variously changed and modified without departing from the spirit of the invention, and that the invention is capable of uses and has advantages not herein specifically described; hence it will be appreciated that the herein disclosed embodiments are illustrative only, and that my invention is not limited thereto.

I claim as my invention:

1. The combination with a snow plow having a bladed rotor to engage and forcibly remove snow or other material, of a jet burner mounted adjacent the rotor and having its jet exhaust positioned to impact the blades of the rotor and to assist in forcible discharge of the material.

2. The combination with a snow plow having a bladed rotor to engage and forcibly remove snow or other material having a guided passageway for the material received from the rotor, of a jet burner mounted adjacent the rotor and having its jet exhaust positioned to assist in forcible discharge of the material, and the jet exhaust being

positioned for discharge through said passageway to accelerate material-discharge.

3. The combination of a rotary snow plow having an engine to drive the plow and its bladed snow-engaging rotor, with a jet burner having an exhaust port positioned to impact the rotor blades and thereby to assist in the operation of the rotary snow plow.

4. The combination of a rotary snow plow having a bladed snow-engaging rotor adapted upon actuation to engage and forcibly remove snow, with a jet burner mounted upon the snow plow, a vaned turbine mounted on the snow plow with its vanes in the path of said jet and adapted to be actuated thereby, and speed-reduction gearing connected to said turbine and to said bladed rotor thereby to drive the rotor and forcibly eject the snow.

5. The combination of a rotary snow plow having an engine to drive the plow and its bladed snow-engaging rotor-shaft, with a vaned turbine borne by said shaft, speed-reduction gearing connecting the turbine to said shaft to drive it and

a jet burner having an exhaust port positioned to impact the vanes of the turbine thereby to actuate the turbine.

5 6. The combination of a rotary snow plow having a bladed snow-engaging rotor adapted upon actuation to engage and forcibly remove snow, with a jet burner mounted upon the snow plow, a vaned turbine mounted on the snow plow with its vanes in the path of said jet and actuated thereby, speed-reduction gearing connected to the turbine and to the rotor thereby to drive the rotor, and a chute to direct the jet-exhaust to facilitate snow removal.

10 15 7. The combination with a snow plow having a bladed rotor to engage and forcibly remove snow or other material, of a jet burner mounted adjacent the rotor and having its jet exhaust adapted to effect rotation of said rotor and to assist in forcible discharge of the material.

EDWARD R. GREER.
